US00D842830S

(12) **United States Design Patent** (10) **Patent No.:** **US D842,830 S**
(45) **Date of Patent:** **** Mar. 12, 2019**

(54) **PORTABLE COMMUNICATION DEVICE**

(71) Applicant: **ICOM INCORPORATED**, Osaka (JP)

(72) Inventors: **Tetsuro Nishida**, Osaka (JP); **Haruki Nishizawa**, Osaka (JP)

(73) Assignee: **ICOM INCORPORATED**, Osaka (JP)

(**) Term: **15 Years**

(21) Appl. No.: **29/613,573**

(22) Filed: **Aug. 11, 2017**

(30) **Foreign Application Priority Data**

Feb. 13, 2017 (JP) D2017-002601

(51) **LOC (11) Cl.** **14-03**

(52) **U.S. Cl.**

USPC **D14/137**

(58) **Field of Classification Search**

USPC .... D14/137, 138 R, 138 AA, 147, 148, 218, D14/155, 159, 142, 225, 226, 191, 188, D14/192, 194, 197, 198; D21/517; D10/104.1, 104.2, 106.1, 65; D13/168 CPC H04B 1/3833; H04B 1/3827; H04B 2001/3861; H04M 1/0202; H04M 1/03; H04M 1/035; H04W 76/005; G08B 21/0202

See application file for complete search history.

(57) **CLAIM**

The ornamental design for a portable communication device, as shown and described.

DESCRIPTION

FIG. 1 is a perspective view of the portable communication device;

FIG. 2 is a front view of the portable communication device;

FIG. 3 is a rear view of the portable communication device;

FIG. 4 is a left side view of the portable communication device;

FIG. 5 is a right side view of the portable communication device;

FIG. 6 is a top view of the portable communication device; and,

FIG. 7 is a bottom view of the portable communication device.

The broken lines depict portions of the portable communication device in which the design is embodied that are not considered part of the claimed design.

1 Claim, 5 Drawing Sheets
